UNITED STATES PATENT OFFICE.

FRANK A. WORDEN, OF BRAWLEY, CALIFORNIA, ASSIGNOR OF ONE-HALF TO D. D. PELLET, OF BRAWLEY, CALIFORNIA.

DESIGN FOR A SET OF PLAYING-CARDS.

46,764.

Specification for Design.

Patented Dec. 8, 1914.

Application filed April 6, 1914. Serial No. 830,057. Term of patent 7 years.

To all whom it may concern:

Be it known that I, FRANK A. WORDEN, a citizen of the United States, residing at Brawley, in the county of Imperial and State of California, have invented a new, original, and ornamental Design for a Set of Playing-Cards, of which the following is a specification, reference being had to the accompanying drawing forming part thereof.

The figure is a plan view of playing cards showing my new design.

I claim:

The ornamental design for a set of playing cards, as shown.

FRANK A. WORDEN.

Witnesses:

D. D. PELLET,
R. CLAYTON LEE.
